UNITED STATES PATENT OFFICE.

MORTON G. BUNNELL, OF CHICAGO, ILLINOIS, ASSIGNOR TO FREDERICK C. AUSTIN, OF CHICAGO, ILLINOIS.

DRAINAGE-EXCAVATOR.

1,169,234.

Specification of Letters Patent.

Patented Jan. 25, 1916.

Application filed July 1, 1903. Serial No. 505,345.

To all whom it may concern:

Be it known that I, MORTON G. BUNNELL, a citizen of the United States of America, and resident of Chicago, Cook county, Illinois, have invented a certain new and useful Improvement in Drainage-Excavators, of which the following is a specification.

My invention relates to excavators of that type in which a runway upon which a bucket travels back and forth serves as a templet or shaping device for determining the cross sectional contour of the ditch. Prior to my invention, excavators of this kind have been so constructed that the wheels or tractors or other supporting devices traveled at each side of the ditch, or entirely at one side thereof. Other arrangements have been employed, but without the results which I desire to attain. With my improved construction, the runway overhangs the rear of the excavator, and the wheels or tractors or other supporting devices are arranged to travel ahead of the said runway. With this arrangement, the ditch is formed behind the excavator, and the latter travels on the ground which is afterward taken up by the bucket. In this way the excavator is adapted to form a wide and more or less shallow ditch the sides of which slope gently and gradually downward from the outer edges thereof to about the center of the excavation. The excavated dirt is dumped at opposite sides of the ditch, and the bucket smooths the inner sides or faces of the two spoil banks, causing the same to form upward continuations of the sides of the excavation. Thus with a relatively shallow excavation a ditch of considerable capacity is made, as the excavation may be of sufficient width to give a good volume of dirt at each side thereof, whereby sloping banks are formed at each side of sufficient height and distance apart at their crests to insure a large carrying capacity for the ditch. In fact the ditch is nearly as wide as the runway is long, and the entire cross sectional contour thereof is determined by the runway. With my improved arrangement, therefore, a large ditch can be made, capable of holding a large volume of water, without going very deep in the ground. The said runway is adapted to be raised above ground, and the construction is such that the entire weight thereof does

not fall on the lifting mechanism, as the outer hinged sections of the runway are carried on the frame of the excavator, and only a portion of the weight thereof is sustained by the lifting devices when the middle section is lifted out of the ground. The runway, although of considerable length, is thus manipulated with more ease and facility than heretofore. The nature and advantages of my invention, will, however, hereinafter more fully appear.

In the accompanying drawings—Figure 1 is a rear elevation of an excavator embodying the principles of my invention, showing the runway in raised position. Fig. 2 is a side elevation of the excavator shown in Fig. 1. Fig. 3 is an enlarged cross section of the runway shown in Fig. 1. Fig. 4 is an enlarged detail view of one of the rack and pinion devices for raising and lowering the frame to the lower end of which the central section of the runway is rigidly attached.

As thus illustrated, my invention comprises a body frame A supported by wheels or tractors or other devices B, two at each side thereof, and two in the middle, whereby the excavator is adapted to travel forward. At its front end there is a boiler C and an engine D for operating the drums E whereby the excavating mechanism is operated. The said excavating mechanism comprises a runway F disposed transversely of the ditch, and overhanging the rear end of the excavator, being composed of a middle section f and outer sections f'. The said runway is supported upon the lower end of a frame G, provided at each side thereof with vertical racks g, which frame is adapted to slide up and down in the stationary frame H, which latter overhangs the rear end of the excavator. The said stationary frame is provided at each side thereof with a shaft g' upon which are mounted pinions g², which latter engage the racks g. These shafts are operated by sprocket chain connections g³, which latter are connected at their lower ends with horizontal and longitudinally extending shafts g⁴. These shafts g⁴ extend forward to the driving mechanism operated by the engine, and have any suitable connection therewith, whereby the power of the engine is used for raising and lowering the runway. The outer sections f'

of the runway have their inner ends pivotally connected at f^2 with the outer ends of the middle section of the runway, and the said outer sections are supported in position by cables I, in the manner shown. These cables have their outer ends attached to the runway sections at i —that is to say, at points some distance back from the outer ends of the runway—and the said cables are then brought upward and over the sheaves i' on the upper end of the stationary frame H. The said cables are then crossed and brought downward around the sheaves h on the stationary frame, and the lower ends of said cables are then attached in any suitable manner to the middle section f of the runway. In this way the weight of the runway, or at least the greater portion thereof, is supported by the cables I and in turn upon the stationary frame of the excavator. Consequently, the raising and lowering mechanism does not sustain all of the weight of the runway, as is ordinarily the case in machines of this kind. When the middle section of the runway is raised, the outer sections move downward slightly, as shown in Fig. 1. In the main, however, as stated, the weight of the outer sections of the runway is employed to counterbalance the middle section, whereby less power is required to raise and lower the runway. The mechanism on the said runway for accomplishing the excavating operation may be of any suitable known or approved character. As shown, the said mechanism consists of a bucket J which travels back and forth thereon, through the medium of rollers or wheels j that engage in the channels of the runway, as shown more clearly in Fig. 3. As shown, this bucket is of the two-way type—that is to say, it is adapted to load by movement in either direction, so that the dirt is dumped first at one side of the ditch and then at the other. The said bucket is operated by cables j' arranged to travel around sheaves j^2 at the outer ends of the runway, and to connect finally with the power operated drum mechanism E, of any suitable form, at the front of the excavator. The bucket may be of any suitable character, and as shown is of the well known type in which the scoop-like structure has a mouth at each end thereof, and a cutting lip J^3 for each mouth. The wall J^4 is movable in the bucket, from one end thereof to the other, and serves to expel the load when the dumping position is reached. The means J^5 for operating said wall, at opposite ends of the runway, may be of any suitable character.

By referring to Fig. 1, it will be seen that the wheels or tractors or other supporting devices B are arranged to travel ahead of the runway, and upon the ground which is afterward taken up by the bucket. The outermost wheels or tractors B travel upon

the outer edges of the dirt that is displaced by the bucket,—that is to say, upon the outer edges of the dirt to be excavated. The runway, it will be seen, is flaring in shape, its outer ends being adapted to form a ditch with gently sloping sides or banks. The middle section of the runway is the only portion that really enters the ground, and it is so shaped that it makes only a shallow excavation. The entire runway is adapted to serve as a templet for determining the cross sectional contour of the ditch. The ditch is shallow but very wide, and the banks thereof slope gently downward from the crest of one spoil bank X to the crest of the other spoil bank X', which latter are of some height above the ground line Y. It will be seen, therefore, that the excavation is very shallow, and that more of the ditch is above the ground line than below. Thus a large ditch of ample carrying capacity is made without going very deep in the ground. This is of considerable advantage, as I find in many cases it is desirable to form a ditch of large capacity without extending the excavation very deep into the ground. Furthermore, and with a runway of the character shown, the excavator is adapted to work in sandy or loose soil, as the banks of the ditch are sloping and not liable to cave in after being formed. As stated, though, the chief advantage of my present improvement is the capability of the excavator of producing a large ditch without the necessity of going very deep into the ground.

The bucket J is preferably provided with a cutter j^6 for operating on the face or end wall X of the excavation. See Fig. 3. This enables the runway to move down to the required depth before moving forward, as said cutter extends outside of the runway—that is, beyond the side of the latter. The cutter J^3 , in other words, maintains a clearance between the runway and the breast of the excavation, thereby permitting the runway and bucket to sink gradually into the ground.

I do not limit myself to the exact construction shown and described.

What I claim as my invention is:

1. In an excavator, a runway consisting of middle and outer sections, means for raising and lowering the middle section, a frame above the middle section, means for imposing some of the weight of the outer sections on the said frame, by connections extending over the said frame and down to the middle sections, whereby the entire weight of the runway does not fall on the raising and lowering means, the said outer sections tending to counterbalance the said middle section.

2. In an excavator, a runway consisting of inner and outer sections, means for raising and lowering the inner section, a body frame, means for imposing some of the

weight of the outer section on the body frame, by causing the outer section to counterbalance the inner section, whereby the entire weight of the runway does not fall on 5 the raising and lowering means, and excavating means adapted to travel on said runway.

3. In an excavator, a body, means for supporting the body entirely in advance of 10 the excavation, permitting any depth and width of ditch in rear thereof, a transverse runway overhanging the rear of said body, having bodily up and down adjustment, means for holding the runway against displacement, 15 a bucket mounted on said runway, movable thereon from one side of the ditch to the other, a cutter operating on the breast of the excavation, directly below the rear end of said body, means for operating 20 said bucket in one direction, means for returning the bucket in the opposite direction, along the same path, said runway being adapted to form a ditch with sloping sides, and means for causing said bucket to discharge 25 on to the ground at the side of the ditch.

4. In an excavator, a body, means for supporting the body entirely in advance of the excavation, permitting any depth and 30 width of ditch in rear thereof, a transverse runway overhanging the rear of said body, having vertical adjustment, means for holding the runway against displacement, excavating means on said runway, adapted to 35 carry the dirt from one side of the ditch to the other, by traveling entirely across the ditch, a cutter operating on the breast of the excavation, directly below the rear end of said body, said runway being adapted to 40 form a ditch with sloping sides, and said excavating means discharging on to the ground at the side of the ditch.

5. In an excavator, a runway consisting of middle and outer sections, means for raising and lowering the middle section, a frame 45 above the middle section, means for imposing some of the weight of the outer sections on the said frame, by connections extending over the said frame and down to the middle 50 sections, whereby the entire weight of the runway does not fall on the raising and lowering means, the said outer sections tending to counterbalance the said middle section, said raising and lowering means comprising 55 a sliding frame on which the runway is carried.

6. In an excavator, a runway consisting of inner and outer sections, means for raising and lowering the inner section, a body 60 frame, means for imposing some of the weight of the outer section on the body frame, by causing the outer section to counterbalance the inner section, whereby the entire weight of the runway does not fall on 65 the raising and lowering means, and exca-

vating means adapted to travel on said runway, said raising and lowering means comprising a sliding frame on which the runway is carried.

7. In an excavator, a body, means for supporting the body entirely in advance of the excavation, permitting any depth and width of ditch in rear thereof, a transverse runway overhanging the rear of said body, having bodily up and down adjustment, 75 means for holding the runway against displacement, a bucket movable back and forth on said runway, from one side of the ditch to the other, said bucket having a mouth at each end thereof, means for operating 80 said bucket, said runway being adapted to form a ditch with sloping sides, means for causing said bucket to discharge on to the ground at the side of the ditch, and means for causing a discharge at the other side of 85 said ditch, which said bucket forms a spoil bank at both sides of the ditch, said bucket operating to slope and smooth the face of each spoil bank to provide a ditch of greater width than depth. 90

8. In an excavator, a body, means for supporting the body entirely in advance of the excavation, permitting any depth and width of ditch in rear thereof, a transverse runway overhanging the rear of said body, having vertical adjustment, means for holding the runway against displacement, excavating means on said runway, serving to carry the dirt from each side of the ditch to the other, said runway being adapted to form 95 a ditch with sloping sides, said excavating means discharging on to the ground at the side of the ditch, and means for causing a discharge at the other side of said ditch, whereby said bucket forms a spoil bank at 100 both sides of the ditch, said bucket operating to slope and smooth the face of each spoil bank to provide a ditch of greater width than depth. 105

9. In an excavator, a runway consisting of middle and outer sections, means for raising and lowering the middle section, a frame 110 above the middle section, means for imposing some of the weight of the outer sections on the said frame, by connections extending over the said frame and down to the middle sections, whereby the entire weight of the runway does not fall on the raising and lowering means, the said outer sections tending to counterbalance the said middle section, 115 said raising and lowering means operating to change the angle of said outer sections when the runway is raised and lowered. 120

10. In an excavator, a runway consisting of inner and outer sections, means for raising and lowering the inner section, a body 125 frame, mechanism for imposing some of the weight of the outer section on the body frame, by causing the outer section to counterbalance the inner section, whereby the 130

entire weight of the runway does not fall on the raising and lowering means, and excavating means adapted to travel on said runway, said mechanism operating to change the angle of said outer sections when the runway is raised and lowered.

Signed by me at Chicago, Illinois, this 18th day of June 1909.

MORTON G. BUNNELL.
